(57) **CLAIM**

The ornamental design for the figurine caricaturing an individual of female gender, as shown and described.

DESCRIPTION

FIG. 1 is a front elevational view of a figurine caricaturing an individual of female gender;

FIG. 2 is a rear elevational view thereof;

FIG. 3 is a left side elevational view thereof;

FIG. 4 is a right side elevational view thereof; and,

FIG. 5 is a top plan view thereof.

The broken lines are included to show portions of the figurine that form no part of the claimed design.
